United States Patent

Des. 235,643
Patented July 1, 1975

235,643

PETCOCK

Wade N. Zimmerman III, Los Angeles, Calif.
(6833 Agnes Ave., North Hollywood, Calif. 91605)

Filed July 23, 1973, Ser. No. 381,391

Term of patent 14 years

Int. Cl. D23—01

U.S. Cl. D23—19

FIG. 3

FIG. 1 is a perspective view taken from the top and front of a petcock, showing my new design;

FIG. 2 is a perspective view taken from the bottom and rear thereof; and

FIG. 3 is a side view thereof.

I claim:

The ornamental design for a petcock, substantially as shown.
